UNITED STATES PATENT OFFICE

ALFRIE E. DIXON, OF MINNEAPOLIS, MINNESOTA

LAMP SHADE AND PROCESS OF MAKING THE SAME

Application filed June 15, 1927. Serial No. 198,929.

This invention relates to ornamental lamp shades and the process of making the same, and especially to lamp shades of the beaded or crystalline type.

5 This invention is an improvement on the invention disclosed in my United States Letters Patent Number 1,585,379, issued May 18th, 1926.

The main object of my present invention 10 is to provide a lamp shade of beautiful appearance, both when illuminated and when not illuminated, comprising a minimum number of parts, and capable of being manufactured at small cost.

15 It is a further object of the present invention to simplify the construction of beaded lamp shades to produce a durable device having a new ornamental appearance without necessitating the use of a skeleton supporting 20 frame.

A still further object is to provide a new beaded lamp shade, wherein the material upon which the beads are affixed constitutes the frame of the shade and moreover contributes greatly to the ornamental effect and general appearance of the finished product.

Another object is to provide a simple but efficient process for manufacturing a beaded lamp shade.

25 These and other objects of the invention will be apparent from the following description made in connection with the accompanying drawings wherein like reference characters refer to similar parts throughout the 30 several views, and in which;

Fig. 1 is a perspective view of a preferred embodiment of my invention, with some portions broken away to show successive layers or strata affixed to the frame;

40 Fig. 2 is a fragmentary cross section taken on an enlarged scale, taken on the line 2—2 of Fig. 1;

Fig. 3 is a plan view of the blank from which the body of the shade is constructed;

45 and

Fig. 4 is a perspective view of a modified form of the invention with some portions broken away.

In the manufacture of the device herein illustrated, a body of finely divided wire netting 5, such as ordinary household screening is utilized. This may be cut to give various shapes and designs, when assembled and in the drawings is shown as cut out in segmental shape.

This blank is next shaped and the lateral edges secured together by any suitable means, such as by paper fasteners or wire.

Said screen body may then be provided with upper and lower reinforced hoops ⁵⁰ *x* and *y*, respectively, if desired, although the same may be omitted. The body so formed is then coated on both sides or embedded in some transparent self-hardening material, such as lacquer or shellac 7, which forms comparatively smooth or glazed surfaces when dry. Pictorial designs 8 may be painted or otherwise affixed to either the inner or outer surfaces of the body so formed and the decorated body may then be coated on both inner and outer surfaces, or if desired, on merely the outer surface with some adhesive transparent self-hardening substance, such as varnish, forming layers 9 on the body, as shown in the drawings.

⁵⁵ Said coatings 9 may be applied by brush, but are preferably effected by dipping the body into the material.

Before coatings 9 have dried or hardened a layer or layers of finely divided transparent particles, such as glass beads or crystals are scattered or blown by an air brush against the adhesive surfaces of the body. Both outer and inner surfaces may be covered by a ⁶⁰ layer 10 of said glass particles or beads if desired. A more beautiful effect is obtained by covering both surfaces.

The upper and lower edges of the shade may be trimmed with ornamental braid or ⁶⁵

metal beading 11 bound around said edges through screening 5.

The product formed will present a very beautiful crystalline appearance and the 5 metal screening will show faintly through the outer layer of beads and through the designs on the shade. The metal screening, when viewed through the layer of beads gives a frosted shimmery effect to the shade, reflecting 10 minute light rays through the beads or crystals when the shade is illuminated. The effect of this netting, viewed through the beads also gives the appearance of etched glass which in combination with the design 15 and colors which may be used is very beautiful and ornamental. The prismatic effect of the shade is greatly intensified when illuminated and if the designs are painted on the inner glazed layer 7 the shade will present 20 a considerably different appearance when illuminated than when not illuminated.

The modification shown in Fig. 4 is similar in every respect to the preferred embodiment with the exception that a light, semi-transparent covering 12 is stretched over the outer surface of the shade proper. This covering 12 may be provided with various ornamental designs and the crystalline effect of the shade will not be present until the shade 30 is illuminated. Thus, as in the patent described in my prior patent heretofore identified, when illuminated the designs painted or affixed to the glazed layers 7 will be brought out and due to the transparency of 35 the fabric covering the crystalline particles will shine through and the shade will have an entirely different appearance than when unlighted.

From the foregoing description it will be 40 seen that I have invented an extremely simple but highly ornamental lamp shade capable of being manufactured at very little expense and requiring a minimum number of parts. The screening constitutes the body of 45 the shade and does not need to be stretched in the manner of cloth shades. No skeleton frame is needed and the netting itself contributes greatly to the ornamental appearance of the completed shade.

50 It will, of course, be understood that various changes may be made in the form, details, proportions and arrangement of parts without departing from the scope of the invention.

55 What is claimed is:

1. A lamp shade comprising a hollow body of metallic netting, a coating of self-hardening transparent material on said body covering the meshes of said netting and permitting 60 the metal to be viewed therethrough, and a layer of glass particles over said coating, said metallic netting reflecting minute light rays through said particles to produce a prismatic effect.
- 65 2. A lamp shade comprising a hollow body

of woven metallic netting, said netting being of sufficient rigidity to hold its shape, a coating of self-hardening transparent material on said body covering the meshes from said netting and permitting the metal to be viewed therethrough, and a layer of transparent prismatic particles over said coating and embedded therein, said metallic netting reflecting and diverting minute rays through said prismatic particles, and moreover being 70 visible therethrough.

In testimony whereof I affix my signature.
ALFRIE E. DIXON.
